UNITED STATES PATENT OFFICE.

JOHN R. FITTON, OF WORCESTER, MASSACHUSETTS, ASSIGNOR TO CROMPTON & KNOWLES LOOM WORKS, A CORPORATION OF MASSACHUSETTS.

FILLING-THREAD-CUTTING MECHANISM FOR WEFT-REPLENISHING LOOMS.

1,091,205.

Specification of Letters Patent. Patented Mar. 24, 1914.

Application filed July 17, 1913. Serial No. 779,533.

To all whom it may concern:

Be it known that I, JOHN R. FITTON, a citizen of the United States, residing at Worcester, in the county of Worcester and State of Massachusetts, have invented certain new and useful Improvements in Filling-Thread-Cutting Mechanism for Weft-Replenishing Looms, of which the following is a specification.

10 My invention relates to filling thread cutting mechanism for weft replenishing looms, in which there is a magazine for superposed bobbins or filling carriers, and transferring mechanism, to transfer a bobbin from the magazine into the active shuttle to take the place of the substantially exhausted bobbin in said shuttle.

20 My invention particularly relates to filling thread cutting mechanism, adapted to clamp, and cut the filling thread on the substantially exhausted bobbin, which is to be removed from the active shuttle.

25 The object of my invention is to provide an improved filling thread cutting mechanism for clamping and cutting the filling thread on the substantially exhausted bobbin which is to be removed from the active shuttle.

30 My invention consists in certain novel features of construction of my improvements in filling thread cutting mechanism, as will be hereinafter fully described.

35 My filling thread cutting mechanism is adapted to be attached to and connected with the transferer arm of the transferring mechanism, and is brought into operative condition through the operation of said transferring mechanism.

40 In the drawings, I have only shown a portion of the loom side with a part of the magazine thereon, and a transferring arm, with my improvements in filling thread cutting mechanism combined therewith, sufficient to enable those skilled in the art to understand the construction and operation thereof.

45 Referring to the drawings:—Figure 1 is an inner end view of the magazine, showing the lay, and breast beam in section, with my clamping, and cutting device left off, looking in the direction of arrow *a*, Fig. 3. Fig. 2 is a view corresponding to Fig. 1, but shows the parts shown in Fig. 1, in a different position, and also shows the clamping, and cutting mechanism, not shown in Fig. 1. Fig.

3 is a plan view of the parts shown in Fig. 1, looking in the direction of arrow *b*, same figure, but shows the clamping, and cutting mechanism in position. Fig. 4 is a sectional view of the cutter, on line 4, 4, Fig. 3, looking in the direction of arrow *a*, same figure. Fig. 5 corresponds to Fig. 4, but shows the parts in a different position. Fig. 6 is an end view of the clamping device, looking in the direction of arrow *a*, Fig. 3. Fig. 7 is a view corresponding to Fig. 6, but shows the clamping device in an open position, and, Fig. 8 is a detached view of the sliding bar, and the levers operated by the same, corresponding in position to Figs. 5 and 7.

70 In the accompanying drawings, 1 is the loom side or end frame, 2 the breast beam, on which is supported—the magazine 4. In the hub 4' on the magazine 4, see Fig. 3, is supported a stud 5, secured therein in this instance by a set screw 5''. On the stud 5 is loosely mounted an angle lever 6, one end of which has a plate 6' thereon with an elongated opening 6'' therein, to receive a bolt 7, which secures the arm of the angle lever 6 to the extension 7'' on the transferer lever 7, shown by broken lines in Figs. 1 and 2. The transferer lever 7 carries a transferer 7''' on the end thereof, to engage the bobbin in the shuttle in the usual way.

75 8 is the lay beam, supported on the lay swords, not shown, 9 is the rear wall of a stationary shuttle box, 10 a shuttle having a bobbin 11 therein.

80 85 All of the above mentioned parts, except the extension 7'' on the transferer lever 7, may be of the usual and well known construction.

90 I will now describe my improvements in filling thread cutting mechanism.

95 12 is a stand secured to the inner side of the breast beam 2. The stand 12 has a boss 12', see Fig. 3, in which is secured, by a set screw 13', a stud 13, having loosely mounted thereon the hub 14' of a two-armed lever 14. The upper end of the lever 14 carries a stud 15, on which is loosely mounted one end of a connector 16; the other end of said connector 16 is loosely mounted on a stud 16', on the end of a downwardly extending arm 100 105 of the angle lever 6, see Figs. 1 and 2. The lower end of the lever 14 is enlarged or flattened, as shown at 14'', Figs. 1 and 2.

110 A plate 17 is secured upon the upper side of the lay 8, see Figs. 1 and 2; the plate 17

has an undercut groove or recess therein, extending transversely of the lay, to loosely receive and guide a sliding bar 18. The bar 18 has its engaging or operating end of curved or cam shape, as shown at 18^c, Figs. 5 and 8, and said bar with this cam shaped end may be termed a cam. The inner end of the sliding cam bar 18 carries a headed stud 18', which extends through an elongated slot 19' in the upper end of a lever 19. The lever 19 has a hub 19' loosely mounted on a stud 20' on the arm 20, secured to the rear side of the lay 8. On the lower end of the lever 19, is a stud 19'', which has loosely mounted thereon a rod head 21, and to which is adjustably secured the threaded end of a rod 22. The rod 22 is loosely supported to have a longitudinal movement in an opening in the lower end of a plate or bar 23, secured at its upper end to the front of the lay 8, and the end of the rod 22 is enlarged, as shown at 22', and is adapted to engage with the enlarged end 14'' on the lever 14. A helically coiled tension spring 24 is secured at one end to the lower part of the plate or bar 23, and at its other end to a projection 21' on the rod head 21. The spring 24 acts to hold the rod 22 in its outward normal position, as shown in Fig. 1.

30 A stand 25 is secured upon the upper side of the breast beam 2, said stand acts to support the filling thread clamping and cutting mechanism.

On the stand 25 is a stud 25', see Fig. 4, on which is loosely mounted the hub 26' of a lever 26. To the lever 26 is secured one blade 27 of the cutter, forming the movable part of the cutter. The stationary blade 28 of the cutter is secured to the stand 25, in this instance by screws 28', see Fig. 4. On a stud or pin 25'', on the upper part of the stand 25, is loosely mounted the hub 29' of a lever 29. The lever 29 at its lower end is adapted to bear against and engage a lug 26'' on the lever 26, see Fig. 5, and through the engagement thereof with said lug 26'' cause the movement of said lever 26 and the opening of the movable blade 27 of the cutter, as shown in Fig. 5.

50 A spring 30 is secured at one end, in this instance by screws 30', to the stand 25, and bears at its free end against the lever 26, and acts to return said lever 26 to its normal position, shown in Fig. 4.

55 The clamping device for clamping the filling thread, consists of a movable clamping jaw 31, having its hub 31' loosely mounted on a screw 32 on the stand 25, Fig. 6. On the pin 25'' is loosely mounted the hub 33' of a second lever 33. The lever 33 has a pin 33'' thereon, which extends through an opening 25''' in the vertical part of the stand 25, see Fig. 7, and engages an extension 31'' on the clamp jaw 31, and acts to open said jaw, 60 or move it away from the stationary part of

the clamp 25^a on the stand 25, when the lever 33 is moved in one direction, as shown in Fig. 7.

A spring 34 is secured at one end on the stand 25, and bears at its other free end 70 against the extension 31'' on the clamp jaw 31, and acts to close said jaw and return it to its normal position.

The sliding bar 18 has a pin 18'' extending up therefrom, which pin is adapted to 75 engage and move forward the filling thread 11', between the clamping jaws, and the cutting blades, on the forward movement of the cam 18.

The cam bar 18 has a recess on one edge, 80 18^a, see Fig. 8, to receive the lever 33, and also has a recess 18^b on its other edge, to receive the lever 29, after the ends of said levers have passed by the cam shaped operating end 18^c of the bar 18, allowing the 85 spring 34 to operate to move down the clamping jaw 31 and clamp the filling thread 11', which has been moved between the clamping jaws, and also allowing the spring 30 to act to move down the movable 90 blade 27, to cut the filling thread between said blade 27 and the blade 28.

From the above description in connection with the drawings, the operation of my improvements in filling cutting mechanism will 95 be readily understood by those skilled in the art.

In the normal operation of the loom the transferrer arm 7 will be in its elevated position, as shown by broken lines in Fig. 1, and the lever 14 will be in the position shown in Fig. 1, and said lever will not engage the enlarged end 22' on the rod 22, as the lay moves forward. The cutting and clamping mechanism will be in closed position, as shown in Figs. 4 and 6. On the substantial exhaustion of the bobbin in the active shuttle, the transferrer mechanism is put into operation in the usual and well known way, to transfer a new bobbin from 100 the magazine into the active shuttle, and the downward movement of the transferrer arm 7 will, through the angle lever 6, and connector 16, move the lever 14 from the position shown in Fig. 1 to the position 105 shown in Fig. 2, the engagement of the enlarged head 22' on the rod 22, with the enlarged end 14' on the lower end of the lever 14, will rock the lever 19, and move forward the cam or bar 18, and the forward end of 110 the bar 18, which is of curved or cam shape, will engage with the downwardly extending levers 29 and 33, and move said levers toward the breast beam, and cause the cutting blade 27 to be opened, as shown in Fig. 5, 115 and also the clamping jaw 31 to be opened, as shown in Fig. 7. The pin 18'' on the cam bar 18 engaging with the filling thread 11' will carry said filling thread between the cutting blades, and also between the clamp- 120 125 130

ing jaws. The continued movement of the cam bar 18 toward the breast beam will allow the ends of the levers 29 and 33 to pass into the recesses 18^b and 18^a, respectively, 5 in the edges of the bar 18. The lever 33 passing first into the recess 18^a, will allow the spring 34 to act to move down the clamping jaw 31 to clamp the filling thread while it is being severed, and the passing of the 10 end of the lever 29 into the recess 18^b, will allow the spring 30 to act to close the cutting blade 27 upon the filling thread 11, to sever the filling thread.

After the filling thread has been severed, 15 the movement of the lay will carry the cam bar 18 away from the breast beam, and through the action of the spring 24 the bar 18 will be returned to its normal position, and also the rod 22, as shown in Fig. 1. 20 The withdrawal of the bar 18 will cause the levers 29 and 33 to pass out of the recesses 18^b and 18^a, and said levers will return to their normal closed positions, as shown in 25 Figs. 4 and 6, all as will be readily understood by those skilled in the art.

It will be understood that the details of construction of my improvements may be varied if desired.

Having thus described my invention, what 30 I claim as new and desire to secure by Letters Patent is:—

1. In a filling thread cutting mechanism, clamping jaws, and cutting blades, on a stationary part of the loom adjacent the 35 magazine, and means to operate, on the operation of the transferring mechanism, said clamping jaws and said cutting blades, said

means including a cam, mounted on and movable relative to the lay, and connections intermediate said cam and the transferring 40 mechanism.

2. In a filling thread cutting mechanism, clamping jaws, and cutting blades, on a stationary part of the loom, adjacent the magazine, and means to operate, on the operation of the transferring mechanism, said clamping jaws and said cutting blades, said means including a cam, having a device thereon to engage and carry the filling thread between said jaws and said blades, 50 said cam mounted on and movable relative to the lay, and connections intermediate said cam and the transferring mechanism.

3. In a filling thread cutting mechanism, clamping jaws, comprising a stationary and 55 a movable jaw, and cutting blades, comprising a stationary and a movable blade, on a stationary part of the loom adjacent the magazine, and means to operate, on the operation of the transferring mechanism, said 60 clamping jaw and cutting blades, said means including a cam, mounted on and movable relative to the lay, and a lever for the movable clamping jaw, and a lever for the movable cutting blade, said levers moved in one 65 direction by said cam, to open said clamping jaw and said cutting blade, and connections intermediate said cam and the transferring mechanism.

JOHN R. FITTON.
